UNITED STATES PATENT OFFICE.

CLARENCE A. HILL, OF COLUMBUS, OHIO, ASSIGNOR TO THE CHAMPION KEROSENE-BURNER COMPANY, OF KENTON, OHIO, A CORPORATION OF OHIO.

KEROSENE-BURNER.

1,377,072.

Specification of Letters Patent.

Patented May 3, 1921.

Application filed October 11, 1919. Serial No. 330,061.

To all whom it may concern:

Be it known that I, CLARENCE A. HILL, a citizen of the United States, residing at Columbus, in the county of Franklin and State of Ohio, have invented certain new and useful Improvements in Kerosene-Burners; and I hereby declare that the following is a full, clear, and exact description thereof, reference being had to the accompanying drawings, which form part of this specification.

This invention is an improvement in kerosene burners, or kerosene gas generating and burning apparatus; and in particular is an improvement upon the kerosene gas generating and burning apparatus shown in patent to A. A. Rusteberg, dated November 4, 1919, No. 1,320,928, and to L. F. Bertrau, dated November 4, 1919, No. 1,320,973, and the objects of the present invention are to produce a kerosene-burner which will have even greater efficiency in operation than the burners above referred to, and by which a more complete generation of gas from the kerosene will be realized, a greater volume of gas produced, and more intense heat obtained.

The invention consists more particularly in the novel construction of the gas generating portions of the apparatus, and the accompanying drawings illustrate a practical embodiment of the invention, which will be hereinafter described; and the essential novel features of the invention are summarized in the claims.

In said drawings:

Figure 1 is a side elevation of the generating apparatus as applied to a rivet heating furnace.

Fig. 2 is an enlarged front view of the apparatus.

Fig. 3 is an enlarged longitudinal vertical sectional view of the generating portion of the apparatus on the line 3—3 of Fig. 4.

Fig. 4 is a horizontal sectional view of the apparatus on the line 4—4, Fig. 3.

The apparatus as shown includes a back pressure gas chamber C, which may be formed within a suitably shaped casting 2. The casting 2 is provided at the bottom with a laterally projecting hollow extension 2^a, which extends to one side of the cylindric portion and communicates with chamber C,

and has an opening in its top near its outer end, which is connected with the mixing tube as hereinafter explained.

The back pressure chamber C is preferably cylindric in cross section and closed at the top and bottom except where it opens into the extension 2^a.

Surrounding this back pressure chamber C exterior to the casting is a coiled generating pipe or retort 1 the inner diameter of the coils thereof being slightly larger than the exterior diameter of the walls of the casing 2; and the latter is provided externally with radial ribs 2^b which serve to properly space the coils from the outer wall of the back pressure gas chamber and keep the coils properly positioned relative thereto. The generating coil may be supported at one side of the casting on the extension 2^a and at the other side by a bracket or clip 2^c attached to the casting as shown.

In the walls of the back pressure gas chamber C are formed a series of perforations 2^d, which are preferably drilled close together in a spiral line opposite the center line of the coils of the generating pipe 1, so that the jets of gas issuing from said apertures will be directed against the coils.

The extremity of the lowermost coil is bent downwardly to form, or is connected with, a vertically disposed reservoir section 1^d below the generating coils, and the lower end of this reservoir section 1^d is connected to the outlet of a valve 1^e, the inlet of which is connected by a pipe 1^f to the kerosene or fuel oil supply, not shown, but preferably a tank from which the kerosene is forced by air pressure into the reservoir 1^d when the valve 1^e is opened, as shown in the Bertrau application aforesaid.

The upper extremity of the generating pipe 1 is connected to or formed with a reducing elbow 1^g, to the outer upper end of which is connected a jet-head or tip 1' which as shown preferably consists of a short tubular section 6 closed at its upper end and having in its side below its closed upper end a small aperture 1^h, through which the gas generated in the retort or generating coil 1 escapes. This tip 1' can be made of brass or other suitable metal very cheaply and simply, and its lower end is externally threaded to readily screw into the elbow 1^g.

Owing to the peculiar form of this jet-head the jet aperture 1° therein will not become clogged with carbon for if any carbon should be carried over by gases generated in the generating pipe 1, such carbon would be directed into the chamber 1^v in the jet-head above the aperture 1°, and be trapped in such chamber and not choke the jet aperture; and this obviates the necessity for frequent cleaning of the jet aperture.

10 The gas issuing horizontally from the aperture 1°, in the jet head is directed into the open end of a mixing tube 4; and air enters such tube adjacent the jet head and 15 mixes with the gas in traversing the mixing tube. This mixing tube is preferably made in two sections 4—4^x united by a T 4^a, and this T is connected by a short vertically disposed tube 4^b with the opening in the extension 2^a of the back pressure chamber. 20 The tube 4^b may support the mixing tube upon the casting 2. Preferably the parts are so arranged that the axes of the tube 4^b and the back pressure chamber C are 25 vertical, and the mixing tube 4—4^x is horizontal.

From the section 4^x of the mixing tube the gaseous mixtures are conducted to the point of utilization. The gases may be conducted 30 from the mixing tube 4^x by a pipe 4^a to a rivet heating furnace 5, as illustrated in the Bertrau application, aforesaid; but obviously may be directed to any desired point of, or means for, utilization thereof.

35 Sufficient gas will enter the back pressure chamber C through pipe 4^b and escape through the apertures 2° and being ignited on the outside of the back pressure chamber will heat the generating pipe 1 and maintain generation of gas therein.

40 Preferably the generating pipe 1 is practically inclosed within a housing or hood G, which is supported upon the top of the casting 2 and depends around the generating pipe and below the chamber C, as indicated 45 in the drawings, but as open at, or has an opening in, its outer end adjacent the jet-head 1' to enable a torch (such as a plumber's torch, not shown) to be applied to the 50 generating pipe 1 to initially heat it and start the generation of gas; or other well known means may be used to initially heat the generating pipe 1.

55 The proportions of the various parts of the oil and gas passages are substantially similar to those described in the Bertrau application aforesaid; except that the generating pipe may be one-fourth inch in internal diameter, instead of three-eighths of an inch 60 in internal diameter; although it may be made of the latter diameter, if desired, or any larger diameter as the various uses of the burner may demand an increased amount of fuel gas.

65 In this construction the generating pipe

or retort is made in the form of a coil, instead of being of U-shape as in the applications aforesaid; and the back pressure chamber C is cylindric instead of oblong in shape, and this enables me to greatly increase the length of the retort or generating pipe 1; and in the example shown the generating pipe is about 72 inches long while in the Bertrau or Rusteberg burners the generating pipe is only about 28 inches in 75 length. By my construction I obtain a better and more complete generation of gas, that is, the kerosene is practically converted into a gas instead of merely or principally vaporized, and thus I obtain a greater 80 volume of fuel gases from a given quantity of kerosene; and this gas will more readily mix with a larger quantity of air and this superior mixture produces more intense heat than a mixture of vaporized oil and air. 85

The gases also flow more evenly through such spiral generating pipe than through a horizontal U-shaped retort, as in a U-shaped retort the vapors rise to the surface of the oil in the pipe and then flow with 90 great rapidity therefrom without becoming thoroughly gasified. My generator can also be started more quickly than Bertrau's or Rusteberg's for the reason that when applying a hand torch to their generators the 95 flame of the torch reaches only one layer of pipe; while in my apparatus the flame of the torch strikes a number of coils of the generating pipe simultaneously thereby heating five times as much surface in the 100 same length of time.

Having described my invention what I claim is:

1. In a gas generating apparatus of the character specified, a back pressure chamber 105 having a cylindric portion provided with a spiral series of perforations in its walls and having a lateral extension below the cylindric portion; a spiral generating pipe surrounding said chamber; a mixing tube; a 110 tube connecting the side of the mixing tube with the lateral extension; means for supplying kerosene to the inlet end of said generating pipe; a jet-head connected with the outlet end of said generating pipe and 115 discharging into the mixing tube.

2. In a gas generating apparatus of the character specified, a casting having a cylindric portion whose interior forms a back pressure chamber provided with a spiral 120 series of perforations in its walls, and ribs on its exterior, and having a laterally projecting portion below the cylindric portion; a spiral generating pipe surrounding the cylindric portion of said casting and spaced 125 therefrom by said ribs; an air and gas mixing tube; a connection between said tube with said laterally projecting portion; valved means for supplying kerosene to the inlet end of said generating pipe, and a jet- 130

- head connected with the outlet end of said generating pipe and having a lateral opening in its side discharging into the mixing tube.
5. 3. In a kerosene gas generating and burning apparatus, a cylindric back pressure gas chamber having a series of jet apertures in its sides and a lateral extension at its bottom communicating with the gas chamber; a spiral generating pipe surrounding the said chamber; an air and gas mixing tube above the casting chamber; a connection between the mixing tube and the lateral extension of the back pressure chamber; valved means 10 for supplying kerosene to said generating pipe; and a vertically disposed jet-head connected with the discharge end of the generating pipe having a closed upper end and an aperture in its side below such upper end 15 adapted to direct gas generated in the generating pipe into the mixing tube.
4. In a kerosene gas generating and burning apparatus, a cylindric back pressure gas chamber having a spiral series of closely adjacent jet apertures in its sides and a lateral extension at its bottom communicating with the gas chamber at its inner end; a spiral generating pipe surrounding the said chamber, said generating pipe having a vertically disposed reservoir section at its receiving end; an air and gas mixing tube above the casting chamber; a tube connecting the mixing tube and the lateral extension of the back pressure chamber; means 20 for supplying kerosene to said reservoir section; and a jet-head connected with the discharge end of the generating pipe adapted to direct gas generating in the generating pipe into the mixing tube.
- 40 5. In a kerosene gas generating and burning apparatus, a casting having a cylindric portion whose interior forms an internal back pressure gas chamber with a spiral series of jet apertures in its sides, and a lateral extension communicating with said chamber; a spiral generating pipe surrounding the cylindrical portion of said casting; an air and gas mixing tube above the casting; a short tube connecting the mixing tube 45 with the lateral extension; a reservoir section at the receiving end of said generating pipe; means for supplying kerosene to said reservoir section; a jet-head connected with the discharge end of the generating pipe adapted to direct gas generated in the generating pipe into the mixing tube; and means for directing gases from the mixing tube to the point of utilization.
6. In a kerosene gas generating and burning apparatus, a casting having a cylindric portion whose interior forms an internal back pressure gas chamber with a spiral series of jet apertures in its sides, and a lateral extension below said chamber and communicating therewith; a spiral generating pipe 55 surrounding the cylindrical portion of said casting; an air and gas mixing tube above the casting; a short tube connecting the mixing tube with the lateral extension; a reservoir section at the receiving end of said generating pipe; means for supplying kerosene to said reservoir section; a jet-head connected with the discharge end of the generating pipe adapted to direct gas generated in the generating pipe into the mixing tube; and means for directing gases from the mixing tube to the point of utilization.
7. In a kerosene gas generating and burning apparatus, a casting having a cylindric portion whose interior forms an internal back pressure gas chamber with a spiral series of jet apertures in its sides, and a lateral extension below said chamber and communicating therewith; a spiral generating pipe 60 surrounding the cylindrical portion of said casting; an air and gas mixing tube above the casting; a short tube connecting the mixing tube with the lateral extension; a reservoir section at the receiving end of said generating pipe; means for supplying kerosene to said reservoir section; a jet-head connected with the discharge end of the generating pipe adapted to direct gas generated in the generating pipe into the mixing tube; and means for directing gases from the mixing tube to the point of utilization.
8. In a gas generating apparatus of the character specified, a back pressure chamber provided with a spiral series of perforations in its walls; a spiral generating pipe 65 surrounding said chamber; and an exterior hood substantially inclosing the chamber and generating coil; with a gas and air mixing tube; means for supplying kerosene to said generating pipe; a jet-head connected with the said generating pipe and discharging into the mixing tube; and a connection between the mixing tube and said chamber.
9. In a gas generating apparatus of the character specified, a back pressure chamber having a cylindric portion provided with a spiral series of perforations in its walls and having a lateral extension below the cylindric portion; a spiral generating pipe surrounding said chamber; and an exterior hood substantially inclosing the chamber and generating coil; with a mixing tube; a tube connecting the side of the mixing tube with the lateral extension; means for supplying kerosene to the inlet end of said 70

generating pipe; a jet-head connected with the outlet end of said generating pipe and discharging into the mixing tube.

10. In a gas generating apparatus of the character specified, a casting having a cylindric portion whose interior forms a back pressure chamber provided with a spiral series of perforations in its walls, and ribs on its exterior, and having a laterally projecting portion below the cylindric portion; a spiral generating pipe surrounding the cylindric portion of said casting and spaced therefrom by said ribs; and an exterior hood substantially inclosing the chamber and generating coil; with an air and gas mixing tube; a connection between said tube with said laterally projecting portion; valved means for supplying kerosene to the inlet end of said generating pipe, and
- 15 20 a jet-head connected with the outlet end of said generating pipe and having a lateral

opening in its side discharging into the mixing tube.

11. In a gas generating apparatus of the character specified, a casting having a cylindric portion whose interior forms a back pressure chamber, provided with a series of perforations in its walls, and a laterally projecting portion below the cylindric portion; a spiral generating pipe surrounding the cylindric portion of said casting and spaced therefrom; an air and gas mixing tube; a lateral connection between said tube and said laterally projecting portion, beside the cylindric portion; valved means for supplying kerosene to the inlet end of said generating pipe; and a jet-head connected with the outlet end of said generating pipe and discharging into the mixing tube.

In testimony that I claim the foregoing as my own, I affix my signature.

CLARENCE A. HILL.
